(57) **CLAIM**

The ornamental design for an electronic device with animated graphical user interface, as shown and described.

DESCRIPTION

FIG. 1 is a front view of an electronic device with animated graphical user interface showing a first image in the sequence showing the claimed design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a rear view thereof;

FIG. 7 is a right side view thereof;

(Continued)

FIG. 8 is a left side view thereof; FIG. 9 is a top view thereof; and, FIG. 10 is a bottom view thereof. The broken lines in the Figures show portions of the electronic device and animated graphical user interface that form no part of the claimed design. The appearance of the electronic device with animated image sequentially transitions between the images shown in FIGS. 1-5. The process or period in which one image transitions to another forms no part of the claimed design.
